COMMUTATOR CONSTRUCTION

Clarence Lynn, Pittsburgh, Pa., assignor to Westinghouse Electric Corporation, East Pittsburgh, Pa., a corporation of Pennsylvania

Application January 10, 1950, Serial No. 137,710

6 Claims. (Cl. 171—321)

1

My invention relates to commutator-type rotor-members of dynamo-electric machines, and it has particular relation to the kind of commutators which are used in high-speed, direct-driven, turbo-generator exciters.

In commutator-constructions of the type to which my invention relates, the commutator-necks are thinner, circumferentially, than the commutator bars. In order to prevent dirt-laden air from passing back through the spaces between the commutator-necks, and depositing a layer of electrically conducting dirt underneath the coil-ends of the armature-winding, and ultimately providing a short-circuiting path of relatively high resistance to ground, it has been customary to fill the space under the coil-ends, between the commutator-necks and the front end of the rotor-core, and also the circumferential spaces between the commutator-necks, with a heat-hardening asbestos filling-compound or cement. This expedient has been practiced for some time, because of the urgency of the necessity for preventing conducting deposits from forming back of the commutator-necks, notwithstanding the fact that it has resulted in a considerable increase in the temperature of the commutator. In some cases, this has presented a considerable problem in keeping the temperature-rise to the guaranteed 55° at rated load-conditions.

It is an object of my present invention to overcome the excessive-temperature difficulty by filling only the back portions of the circumferential spaces between the commutator-necks, leaving substantially large unfilled spaces between the front portions of the commutator-necks, thus causing said front portions of the necks to act as fan-blades and as heat-radiating surfaces for conducting heat away from the commutator-bars. In one instance, this expedient has resulted in as much as an 18° reduction in the commutator-temperature. In the high-speed machines to which my invention is more particularly applicable, it is necessary or desirable to use banding around the commutator-necks, in order to restrain them against centrifugal force, and when my present invention is used, this banding is applied only over the filled rear portions of the commutator-necks.

In commutator-constructions of the type having solid necks, or necks which are thick in a circumferential direction, so that there is substantially no space between adjacent necks, it has been customary, heretofore, to use a filling-cement or compound back of the necks, and underneath the coil-ends of the armature-winding, but these constructions have lacked the spaced thin front neck-portions which act as fan-blades

2

and heat-dissipating surfaces in accordance with my invention.

With the foregoing and other objects in view, my invention consists in the structures, combinations, parts, and methods of design and operation, hereinafter described, claimed and illustrated in the accompanying drawing, wherein:

Figure 1 is a fragmentary longitudinal section of a portion of a dynamo-electric machine, illustrating my invention, the section-plane being indicated by the broken line I—I in Fig. 3;

Fig. 2 is a fragmentary transverse sectional view along the line II—II in Fig. 1, with a portion of the figure broken back to show a section along the line IIa—IIa of Fig. 2, and

Fig. 3 is a fragmentary cylindrical section on the line III—III of Figs. 1 and 2.

I show my invention applied to a dynamo-electric machine having a stator-member 1 and a rotor-member 2. The rotor 2 has a core 3 mounted on a shaft 4. Spaced axially from the front end of the rotor-core, is a commutator 5, which is illustrated as comprising a plurality of commutator-bars 6 and mica bars 6' (Figs. 2 and 3), which are held in place by a shrink-ring 7 (Fig. 1), which is centered and supported within a centering-plate 8. The centering-plate 8 is supported on a commutator-bush or shell 9, which is mounted on the shaft 4, in accordance with a known construction. The centering-plate 8 also has a portion extending radially outwardly far enough to constitute a coil-support 10.

The commutator 5 is also provided with a plurality of commutator-necks 16 which are thinner, circumferentially, than the bars 6, said commutator-necks being set into, and securely fastened within, suitable saw-cuts 17 (Figs. 1 and 2) in the respective bars, in accordance with a known construction. The top portions of the necks 16 are electrically connected to the front ends 18 of the armature-coils or winding, as is known.

In accordance with my invention, I provide a suitable insulating filling 20, which is illustrated as including a hardenable insulating cement or filling-compound 21, and a plurality of neck-wedges 22. The cement 21 is introduced into the space under the coil-ends 18, between the commutator-necks 16 and the front end of the rotor-core, construing the insulating-pad 23 and the centering-plate 8 (when used) as constituting the front end of the core-construction 3. The idea is, to fill the space underneath the coil-ends 18, so that no conducting deposit may be carried there by the ventilating-air. The insulating-pad 23 is used between the two layers of the front end-windings of the armature, in the case of a two-layer armature-winding.

In the particular illustrated form of my in-

vention which is shown in the drawing, I preferably use a plurality of neck-wedges 22 which are made of solid insulating material, and which are disposed between the rear portions of the circumferential spaces between the commutator-necks 16, thus leaving substantially large unfilled spaces 24 between the front portions of the commutator-necks. In the particular form of embodiment which is shown in the drawing, the coil-ends 18 are disposed at one side of the respective necks 16 to which they are attached, and the respective neck-wedges 22 are disposed between the other sides of these coil-ends 18, and the other side of the next adjacent neck 16, leaving spaces 25, under the coil-ends 18. These spaces 25 are also filled with cement 21.

In operation, the essential feature of my invention is that the necks 16 shall be thinner, circumferentially, than the commutator-bars 6, so that there is a circumferential spacing between successive necks. The rear halves, or other suitable portion, of this between-neck spacing is filled by a suitable filling, which is generically indicated at 20 in the drawing, and which may consist of cement alone, or suitably fitted neck-wedges alone, or, as shown, partly cement and partly the neck-wedges. It is important that the front spaces 24 should be left unfilled, occupying the front half-inch, or other substantially large portion, of the spaces between the successive necks.

In the particular form of invention which is illustrated in the drawing, the neck-wedges 22 are wide enough, in an axial direction, to extend backwardly for about a quarter of an inch behind the rear ends of the commutator-necks 16, and these rearwardly extending portions of the wedges 22 are provided with vertical grooves 26, or other means for providing shoulders 27 (Fig. 3) for interlocking engagement with the filling-compound 21, so that the filling-compound helps to hold the wedges in place.

When my invention is applied to high-speed machines, such as turbo-excitors, it is necessary, or quite desirable, to use banding 28, both over the coil-ends 18, and over the rear filled portions of the spaces between the commutator-necks 16, but this banding should not extend over the front unfilled spaces 24 between the necks. The banding thus serves to retain both the necks 16, and the neck-wedges 22, against centrifugal force. At the same time, the banding does not extend forward far enough to interfere with the radial air-flow which is induced by the spaced front halves of the necks 16.

Experience has shown that my invention results in just as good prevention of short-circuiting deposits by the dust- and dirt-laden ventilating-air, as in the previously used constructions. The banding which extends over the rear halves of the necks adequately retains the necks against centrifugal force, and when my neck-wedges 22 are used, this banding also adequately retains the wedges against centrifugal force. At the same time, the omission of the banding over the unfilled front spaces 24 between the commutator-necks, leaves an unimpeded path for the free radial blast of ventilating-air, which is produced by the fan-blade action of the front halves of the necks. In one particular instance, the introduction of my invention produced a commutator having a temperature-rise of 43° C., which is 12° below the usual guarantee, whereas, with the old form of construction, without the unfilled substantially large front spaces 24, the temperature- 75

rise was 61°, or 6° over the guaranteed temperature-rise.

While I have illustrated and described my invention in a single form of embodiment, which is at present preferred, it will be obvious that my invention is susceptible of considerable variation, by way of additions, omissions and the substitution of equivalents, without departing from the essential spirit of the invention. I desire, therefore, that the appended claims shall be accorded the broadest construction consistent with their language.

I claim as my invention:

15. A commutator-type dynamo-electric machine having a rotor-core, an armature-winding carried by the rotor-core, a commutator spaced axially from the front end of the rotor-core, said commutator comprising a plurality of commutator-bars, and commutator-necks which are thinner, circumferentially, than the bars, said commutator-necks being set into, and securely fastened to, the respective bars, electrical connections between the commutator-necks and the coil-ends of the armature-winding, and a filling including a hardenable insulating filling-compound, said filling occupying the space under the coil-ends, between the commutator-necks and the front end of the rotor-core, and also filling the rear portions of the circumferential spaces between the commutator-necks, leaving substantially large unfilled spaces between the front portions of the commutator-necks.
20. The invention as defined in claim 1, characterized by said filling comprising also solid neck-wedges disposed between said rear portions of the commutator-necks.
25. The invention as defined in claim 1, characterized by said filling comprising solid neck-wedges disposed between said rear portions of the commutator-necks, said neck-wedges extending to the rear of said commutator-necks and having shoulder-portions for interlocking engagement with said filling-compound.
30. The invention as defined in claim 1, in combination with banding around said coil-ends and around said filled portions, but not around the unfilled portions, of the commutator-necks.
35. The invention as defined in claim 1, in combination with banding around said coil-ends and around said filled portions, but not around the unfilled portions, of the commutator-necks, said filling comprising also solid neck-wedges disposed between said rear portions of the commutator-necks.
40. The invention as defined in claim 1, in combination with banding around said coil-ends and around said filled portions, but not around the unfilled portions, of the commutator-necks, said filling comprising solid neck-wedges disposed between said rear portions of the commutator-necks.
45. The invention as defined in claim 1, in combination with banding around said coil-ends and around said filled portions, but not around the unfilled portions, of the commutator-necks.
50. The invention as defined in claim 1, in combination with banding around said coil-ends and around said filled portions, but not around the unfilled portions, of the commutator-necks, said filling comprising solid neck-wedges disposed between said rear portions of the commutator-necks.
55. The invention as defined in claim 1, in combination with banding around said coil-ends and around said filled portions, but not around the unfilled portions, of the commutator-necks, said filling comprising solid neck-wedges disposed between said rear portions of the commutator-necks.
60. The invention as defined in claim 1, in combination with banding around said coil-ends and around said filled portions, but not around the unfilled portions, of the commutator-necks, said filling comprising solid neck-wedges disposed between said rear portions of the commutator-necks.
65. The invention as defined in claim 1, in combination with banding around said coil-ends and around said filled portions, but not around the unfilled portions, of the commutator-necks, said filling comprising solid neck-wedges disposed between said rear portions of the commutator-necks.
